LATCH OPERATING MECHANISM

Clarabelle E. Rundel, Southfield Township,
Oakland County, Mich.

Application August 11, 1945, Serial No. 610,263

1 Claim. (Cl. 292—222)

1

My invention relates to a new and useful improvement in an ornamental latch-operating device, adapted for mounting on doors and similarly movable bodies which are fastened together by means of a latch mechanism. On such devices as doors, drawers and the like, a latch mechanism is frequently provided which is releasable by a plunger which is pressed inwardly in order to release the latch. It is common on such devices to provide in addition to the inwardly directed plunger which has to be pressed in in order to release the latch, a handle whereby the door or drawer may be swung or moved. In the present invention I provide an ornamental structure which is neat and attractive in its appearance and which serves as a means for forcing the plunger in to release the latch and at the same time affords a means for moving the object when the latch has been released. It is an object of the present invention to provide a device of this class which will be simple in structure, economical in manufacture, durable, compact, easily and quickly installed, attractive in appearance and highly efficient in operation.

It is another object of the present invention to provide a device of this class in which a supporting body is provided with a swingably mounted member which will serve as a cam when swung upwardly or into operative position.

It is another object of the present invention to provide in a device of this class a supporting escutcheon having a pendant swingably mounted thereon and provided on its rear face with a plunger engaging cam face.

Other objects will appear hereinafter.

It is recognized that various modifications and changes may be made in the detail of structure illustrated and it is intended that such shall be embraced within the scope of the claim which forms a part hereof. Forming a part of this application are drawings in which,

Fig. 1 is a front elevational view of the invention,

Fig. 2 is a sectional view taken on line 2—2 of Fig. 1,

Fig. 3 is a sectional view taken on line 3—3 of Fig. 1,

Fig. 4 is a fragmentary sectional view taken on line 4—4 of Fig. 2.

Fig. 5 is an elevational view of a slight modification of the invention.

Fig. 6 is a sectional view similar to Fig. 3, showing a different form of mounting.

In the drawings I have shown the invention mounted on a door 7 which is in swingable rela-

2

tion to the frame 8. Mounted on the door 7 is a latch housing 9 having the latch 10 which is adapted to latch the door 7 in closed relation to the frame 8. This latch 10 is actuated by the plunger 11 which is normally pressed outwardly by a spring 11A and which is pressed inwardly against the compression or tension of the spring in order to release the latch. This latch mechanism may be of any well known structure and of itself forms no part of the present invention and is illustrated merely for the purposes of exemplifying the invention.

The invention comprises a supporting plate or escutcheon cam 12 which is mounted upon the door 7. This plate 12 may be of any ornamental shape or appearance and may be formed of any desirable color. The plate 12 is provided with the outwardly projecting boss 13 which serves to form a housing in the front wall of which is formed a slot 14. Supported by this plate 12 and depending therefrom is a pendant which serves both as a handle for swinging the door 7 and as a means for actuating or pressing inwardly the plunger 11. In the drawings I have shown this pendant comprising a ball 15 projecting outwardly from which is a neck 16 carrying at its end a head 17. This pendant may of course be formed from any desirable material and may be of any desired color. The head 17 is preferably formed spherical and on the inner side thereof a groove 19 is formed to provide a cam surface, the plunger 11 being in alignment with and projecting inwardly of this groove 19.

As clearly shown in Fig. 2, this groove varies in depth so that the cam surface is provided. When the member 15 is swung upwardly toward the dotted line position shown in Fig. 2, the plunger 11 riding in the cam groove will be forced inwardly to release the latch and the operator may then use the member 15 as a handle to swing the door or to draw outwardly a drawer or similarly movable body on which the invention is mounted. It is believed obvious that the member 13 serves as a socket in which the head 17, which is preferably cylindrical or spherical, is mounted. However the engagement of the plunger 11 in the cam groove 19 prevents a rotation of the pendant on the axis of its neck. When the pendant is swung upwardly so that the plunger reaches the end of the groove 19 the plunger will be forced inwardly to releasing position while still slightly engaging in the groove 19. The length of the slot 14 will of course limit the upward swinging of the member 15.

The groove 19 as shown in Fig. 2, lies in a plane

which passes through or extends longitudinally of the axis of the neck 16 of the pendant. In Fig. 5, I have shown a slight modification in which the groove 19A formed in the head 17A is carried by the neck 16A of the pendant 15A and in which engages the plunger 11A lies in a plane extended at right angles to the axis of the member 16A. With this form the release of the latch mechanism may be effected in the same manner as is accomplished by the preferred form shown in Fig. 1 and Fig. 2. However, in the form shown in Fig. 5 the pendant may be rotated on the axis of the neck 16A without dis-engaging the plunger from the groove 19A.

In Fig. 6, I have shown a slight modification in which a pin 18 is directed through a head 17B and through the side walls of the housing 13 so that the structure is pivotally mounted by means of the pin and the supporting by means of a ball and socket arrangement is not resorted to.

In a device of this kind constructed as illustrated it becomes possible to provide a door latch releasing member which will also serve as a handle and which may be of highly ornamental appearance. Particularly is this so when the parts are formed from vari-colored plastics.

What I claim as new and desire to secure by Letters Patent is:

A device of the class described adapted for use with a latching mechanism having a longitudinally moveable latch releasing plunger, comprising a supporting body adapted for mounting on a supporting structure with which said latching

mechanism is used; a socket forming housing on said body and the socket therein being opened at its lower end and said housing having an outer wall with a vertically extending slot formed therein extending upwardly from the lower edge thereof and communicating with the socket; a pendant comprising an elongated neck having a ball at its lower end and provided at its upper end with a spherical head, said head having a groove formed therein extending from its lower end to its upper end and lying in a plane parallel with the axis of said neck, said groove being deeper at its lower end than at its upper end, said head being positioned in said socket to provide a pivot on which said pendant may be swung upwardly and downwardly, one end of said releasing plunger engaging in said groove, the surface of said groove, upon swinging of said pendant upwardly, effecting longitudinal movement of said releasing plunger, and said releasing plunger in engagement with the sides of said groove preventing rotation of said head in said socket.
